CLAIM

The ornamental design for an apparatus for applying cosmetics, as shown and described.

DESCRIPTION

FIG. 1 is a front perspective view of an apparatus for applying cosmetics;

FIG. 2 is a first side view of the apparatus of FIG. 1;

FIG. 3 is a close up view along sight lines as shown in FIG. 1;

FIG. 4 is a close up view along sight lines as shown in FIG. 2;

FIG. 5 is a second side view of the apparatus of FIG. 1;

FIG. 6 is a third side view of the apparatus of FIG. 1;

FIG. 7 is a close up view along sight lines as shown in FIG. 5;

FIG. 8 is a close up view along sight lines as shown in FIG. 6;

FIG. 9 is a fourth side view of the apparatus of FIG. 1;

FIG. 10 is a close up view along sight lines as shown in FIG. 9;

FIG. 11 is a top view of the apparatus in FIG. 1; and,

FIG. 12 is a bottom view of the apparatus in FIG. 1.

The broken lines represent portions of the structure that form no part of the claim.

1 Claim, 3 Drawing Sheets
